FEELER-MOTION FOR LOOMS.

1,294,534.

Specification of Letters Patent. Patented Feb. 18, 1919.

Application filed March 6, 1918. Serial No. 220,681.

To all whom it may concern:

Be it known that I, ALONZO E. RHOADES, a citizen of the United States, residing at Hopedale, county of Worcester, State of Massachusetts, have invented an Improvement in Feeler-Motions for Looms, of which the following description, in connection with the accompanying drawing, is a specification, like characters on the drawing representing like parts.

This invention is concerned with the so-called feeler motion for automatic looms. Such a motion is utilized to ascertain the substantial exhaustion of the filling on the filling carrier in the active shuttle of the loom and when such a substantial exhaustion has taken place then to initiate a change in the operation of the loom, usually the automatic replenishment of the filling by substitution of a fresh filling carrier for the substantially exhausted filling carrier.

In order that the wastage of filling may be as small as possible it is obviously desirable that the feeler motion shall initiate the operation of filling replenishment when there is just sufficient filling left on the running filling carrier to enable the filling carrier to lay a full pick in the shed upon the last pick of the shuttle preceding replenishment. It is necessary, therefore, that the feeler motion should be actuated in a most accurate manner and should be able to respond to any usual position which the filling carrier may occupy.

It is the object of the present invention to provide a feeler motion for looms in which provision is made for the actuation of the feeler upon the predetermined degree of exhaustion of the filling carrier notwithstanding the considerable variation in the vertical position of the filling carrier and the angular relation of the filling carrier with respect to the feeler.

When as is usual the filling carrier is a bobbin or cop supported in a shuttle there are several variations of position which may not infrequently take place. The shuttle when boxed opposite the feeler may assume a position slightly above the race plate and thus present the filling carrier slightly above the normal feeling position. This is due to the lifting or tipping of the shuttle in the shock and jar consequent to the boxing of the shuttle. Again

the filling carrier itself may be positioned at a slight angle to the longitudinal axis of the shuttle. In the automatic loom the filling carrier is usually held by clamping devices gripping the butt of the filling carrier and if the filling carrier when positioned in these clamping devices is not positioned with great accuracy it may assume the undesirable angular position.

The present invention is embodied in a feeler motion in which a feeling instrumentality is of the type having a penetrating point which at each beat up enters the mass of filling without effect until the mass of filling is exhausted to the predetermined degree when the penetrating point coming into contact with the hard surface of the filling carrier itself thereupon acts to effect initiation of the weft replenishing operation.

The present invention presents a feeler in which a plurality of these penetrating points are arranged in two horizontal rows so that notwithstanding a variation in the vertical position of the filling carrier one or the other of the penetrating points will come into coöperative relation therewith and these penetrating points are further spaced laterally to a sufficient extent so that notwithstanding any reasonable angular mispositioning of the filling carrier one or the other of the penetrating points will also come into effective coöperation with the filling carrier so that irrespective of the precise angular or vertical position of the filling carrier with respect to the feeler one or more of the penetrating points will engage the surface of the filling carrier upon substantial exhaustion of filling and act to effect the initiation of filling replenishment.

These and other objects of the invention will appear more fully from the accompanying description and drawings and will be particularly pointed out in the claims.

The drawings represent so much of the well known type of Northrop automatic filling replenishing loom as is necessary to a disclosure of the present invention.

In the drawings,

Figure 1 is a top plan view of a portion of the loom with the central portion broken away and showing a feeler motion of preferred construction embodying this invention;

Fig. 2 is a top plan view on a larger scale of the feeler motion detached from the loom frame;

Fig. 3 is a view in vertical cross section 5 of the construction shown in Fig. 2;

Fig. 4 is a detail taken in cross section to the filling carrier and showing the feeler just contacting with the filling thereon.

It will be unnecessary to describe in detail 10 the general construction and operation of a loom of this type because it is well known and familiar to those skilled in the art. The loom frame comprising the loom sides 1 and 2 supports at the front the breast 15 beam 3. The lay 4 swings toward and from the breast beam in the usual manner and carries at each end the shuttle boxes 5 and 6 respectively.

At the transfer end of the loom the usual 20 hopper or feeder 7 is mounted from the breast beam and carries the supply of fresh filling carriers which upon the replenishing action taking place are successively transferred to the shuttle then boxed beneath the 25 hopper. This replenishing action is usually operated from a starter rod or shaft 8 running along the front of the loom. A latch 9 is so connected to the starter rod that when the latch is pushed forwardly it rocks the 30 rod 8 and sets into operation the filling replenishing mechanism.

The usual weft fork 10 which acts to stop the loom or effect weft replenishment upon the absence or failure of the filling in the 35 shed is shown and in connection therewith the usual weft hammer 11 which constitutes a vibrating actuator rocked or vibrated from the mechanism of the loom in a well known and familiar manner. It will thus be seen 40 that if the latch 9 be lifted into the path of the weft hammer 11 the weft hammer will act to push the latch back rocking the starting rod 8 and so effecting filling replenishment. The feeler motion here shown as an 45 embodiment of the invention acts through a well known type of mechanism to raise this latch 9 into the path of the weft hammer 11 upon indication of substantial exhaustion of filling in the active filling carrier.

The feeler motion as shown comprises a two-part box-like stand 12 the parts being secured together by the screws 13. This stand is held in properly adjusted position 55 on the breast beam by set screws 14 passing through the longitudinal slot 15 into the breast beam.

This stand carries longitudinally sliding therein the feeler slide 16 which in general 60 shape is a long flat metal plate the end portion 17 of which is narrower than the forward portion. A helical spring 18 surrounds the narrow portion 17 abutting at its rear end against the forward end of the 65 wider portion and abutting at its front end

against the interior of the stand 12 so that this spring normally acts to maintain the feeler slide in rearward projected position. The limit of rearward projection of the slide is adjustably determined by a set screw 70 19 passing through a bracket 20 arising from the feeler slide and abutting a vertical arch 21 on the feeler stand.

At its rear end the feeler slide terminates in a box-like casing formed by a cover plate 75 22 flanged at its side and secured by pins 23 and set screws 24 to the body of the slide 16. The rear end of this casing presents an impinging face 25 which is adapted to contact 80 with the filling on the filling carrier.

In the rear of the casing 22 the filling slide carries mounted rigidly thereon a medially and vertically slotted bracket 26 in which is journaled on a horizontal journal pin 27 a finger 28. This finger presents a 85 forward notched end 29. When the finger is in its normal or lower position shown in Fig. 3 and the feeler slide is reciprocated forwardly the finger passes beneath the end of a controller 30. This controller is vertically pivoted at 31 on the breast beam and held in rearward position by a suitable spring 32.

If, however, the finger 28 be swung on the pivot 27 to raise its forward end 29 it 90 will catch upon the end of the controller 30, upon the rearward reciprocation of the feeler slide and swing the controller rearwardly. In the construction as arranged 95 when this operation takes place the controller 30 riding in the cam slotted ear 33 of the transmitter 34 fulcrumed at 35 on the breast beam will rock the transmitter and cause it to elevate the latch 9 into the path of the weft hammer 11 and thus actuate the filling 100 replenishing mechanism.

The rocking of the finger 28 is effected by the member which carries the penetrating points. This member is shown as a skeleton plate 36 mounted to slide in the box-like casing at the rear end of the feeler slide and limited in its extreme movements by pins 37. This plate 36 is narrowed at its forward end and projects from the box-like casing into the slotted portion of the bracket 26. At its 110 forward end it cooperates with a longitudinally adjustable portion of the finger 28 herein shown as a plate 38 held in adjusted position by set screws 39. A helical spring 40 is located between the plate 22 and a rearwardly projecting end 41 of the finger 28 and acts to maintain the finger in its normal 115 or lowered position. The member 36 carries at its rearward edge a plurality of rearwardly projecting penetrating points 42, 43, 44 and 45. The number may vary but four such points are herein shown. These points are arranged in two rows vertically separated the upper row being constituted by the points 43 and 45 and the lower row by the 120 points 42 and 44. A helical spring 46 is 125 located between the plate 38 and the rearwardly projecting end 41 of the finger 28 and acts to maintain the finger in its normal or lowered position. The member 36 carries at its rearward edge a plurality of rearwardly projecting penetrating points 47, 48, 49 and 50. The number may vary but four such points are herein shown. These points are arranged in two rows vertically separated the upper row being constituted by the points 48 and 50 and the lower row by the 130

points 42 and 44. Furthermore, the arrangement of these points is a staggered relation so that the points in the upper row alternate in horizontal position with the 5 points in the lower row. Again it will be noted that the points are sufficiently separated laterally or in the direction of the length of the filling carrier that they extend over a considerable distance longitudinally 10 of the filling carrier. The corners 46 of the feeler slide and casing are also rounded off so that there will be no danger of an angularly mis-positioned filling carrier being held out of contact with the endmost penetrating points by the filling slide. 15

In the operation of the mechanism as the lay beats up the feeler slide enters the usual slots in the shuttle box and wall of the shuttle and the end of the feeler slide comes in 20 contact with the mass of filling on the filling carrier. At each beat up the impinging face 25 contacts with the exterior of the mass of filling and the penetrating points enter the mass of filling. During this operation the parts are positioned as shown in 25 Fig. 3 of the drawing and as the penetrating points enter the mass of filling no operation of the finger 28 takes place but the feeler slide simply moves forwardly with the lay. 30 This operation continues until the filling on the filling carrier is substantially exhausted when upon the next beat up one or more of the penetrating points will come into contact with the hard exterior surface of the 35 body of the filling carrier and, as the beat up continues, the filling carrier pressing against the penetrating points pushes the slideable plate or member 36 until it in turn presses against the plate 38 and thus swings 40 the finger 28 into elevated position whereupon the end 29 catches against the controller 30 and, as the beat up continues, the feeler slide moves forwardly and effects through the mechanism already described 45 the initiation of filling replenishment.

Owing to the location and position of the penetrating points it will be seen that even if the filling carrier is for any reason somewhat above or below its normal position it 50 will still come into contact with one or the other of the vertically spaced rows of penetrating points and so also if the filling carrier is somewhat angularly mis-positioned in

any direction it will come into contact with one or the other of the penetrating points 55 in one or the other of the two rows. Thus a wide degree of variation from proper horizontal position of the filling carrier may take place and still one or the other of the penetrating points will upon substantial exhaustion of filling indicate that fact by coming into contact with the surface of the filling carrier and at such a point on its surface as properly to indicate substantial exhaustion. It will be observed that if the feeler 60 is operated accurately the penetrating point effecting its operation must contact with the filling carrier at some point substantially along that element of the cylindrical surface of the filling carrier line in an axial plane 70 coinciding with the axis of the feeler reciprocation. This will be substantially secured by the present invention notwithstanding reasonable variations in vertical position and angular relation of the filling carrier 75 with respect to the feeler.

Having fully described my invention, what I claim as new and desire to secure by Letters Patent is:

1. A feeler motion for looms comprising a 80 feeler slide having an impinging face, a member slideable therein and provided with an upper row and a lower row of spaced rearwardly projecting penetrating points, the ends of the feeler slide at the impinging 85 face being rounded off to permit the endmost penetrating points to engage an angularly mis-positioned filling carrier, and means for effecting initiation of filling replenishment upon forward movement of said 90 slideable member with respect to the feeler slide, whereby, irrespective of the precise angular or vertical position of the filling carrier with respect to the feeler slide, one or more of said penetrating points will engage 95 the surface of the filling carrier upon substantial exhaustion of filling and thus effect the initiation of filling replenishment.

2. A feeler motion for looms as defined in claim 1 in which the penetrating points 100 of the upper row are staggered with respect to those of the lower row.

In testimony whereof, I have signed my name to this specification.

ALONZO E. RHOADES.
